UNITED STATES PATENT OFFICE.

PETER WIEDERER, OF STAPLETON, NEW YORK.

DESIGN FOR A MIRROR-FRAME.

SPECIFICATION forming part of Design No. 24,404, dated June 18, 1895.

Application filed May 17, 1895. Serial No. 549,704. Term of patent 7 years.

To all whom it may concern:

Be it known that I, PETER WIEDERER, a citizen of the United States, residing at Stapleton, in the county of Richmond and State 5 of New York, have invented and produced a new and original Design for Mirror-Frames, of which the following is a specification, reference being had to the accompanying drawing, which shows a front elevation of a mirror embodying my design.

The leading feature of my design consists in a ring or frame apparently supported on the back or shoulders of a clown in squatting position whose head projects into the frame 15 and whose arms are akimbo and rest upon the legs, which form the supports for the article.

A is the circular frame of the mirror B which has the appearance of being supported on the back or shoulders of a clown, whose head C 20 is crowned by a clown's cap D and projects into the interior of the frame. The clown is

represented as in squatting position with the legs E spread or in straddling position, and with the arms F akimbo, so that the frame appears to merge into the elbows, while the 25 hands rest on the thighs. The jacket G is represented with cuffs H and with a fringe I around the bottom, and is also provided with a scalloped frill J at the neck. Short pants K, stockings L and slippers M are represented 30 on the legs and feet of the clown.

What I claim is—

The design for a mirrorframe, herein shown and described.

In testimony that I claim the foregoing as 35 my invention I have signed my name in presence of two subscribing witnesses.

PETER WIEDERER.
